UNITED STATES PATENT OFFICE.

ARTHUR WILLIAM GREEN, OF HAILSHAM, JAMES ROBERT GREEN, OF EASTBOURNE,
AND PERCY FRENCH, OF HAILSHAM, ENGLAND.

LOOM FOR WEAVING WHEREIN THE WEFTS ARE DRAWN FROM STATIONARY SUPPLIES.

Application filed May 4, 1925, Serial No. 27,883, and in Great Britain May 5, 1924.

This invention relates to the mechanism for operating the weft threads in looms for weaving wherein the wefts are drawn from stationary supplies and such mechanism is 5 specially applicable for use with the invention set forth in our prior British Patent No. 168,444 dated June 14, 1920, but it must be understood that the present invention is 10 also applicable for use with other classes of looms for weaving wherein the wefts are drawn from stationary supplies.

The present invention will be described as applicable to the machine set forth in our prior patent, and will be fully understood 15 from the following description aided by the annexed drawings.

Figure 1 is a side elevation of a portion of a loom frame with two of our reciprocating rods or tubes carrying weft threads and also showing cooperative selvedge shuttles and their carrier, the reciprocatory rods or tubes being in the starting position for applying the weft threads across the fabric.

Figure 2 is a plan of the two reciprocating rods or tubes and the cooperating shuttles and their carrier shown in Figure 1.

Figure 3 is a side elevation of a selvedge shuttle and its carrier.

Figure 4 is a plan with a portion of the carrier broken away to show the selvedge shuttles.

We employ singly or in multiple, as required, rods or tubes or pairs of multiples of pairs of rods or tubes (in the drawings we show a pair 28, 28) positioned parallel and each or each pair or the whole are connected at or near the outer end to a device comprising a sleeve A or carriage slideable upon a bar or bars or track or tracks 52, to prevent revolution, such device A or devices being reciprocated by any desired mechanism.

At the inner end of each rod 28 we pivot, in rule joint fashion, an arm B having an eye or roller 31 or other means for carrying a weft thread 29. The warp threads are shown at P.

Each weft thread is run from a reel 34, constituting a stationary weft supply, over 50 rollers C, C¹ one of which, C¹ is capable of being braked to apply tension to the thread, and then around a roller or rollers D or eyes on the rod 28 to the eye or roller 31 in the arm B and connected with the material

E from which, for example, a door mat is 55 being made.

Each shuttle 36 is formed with a curved nose piece F and with extension pieces G at top and H, H at bottom and each shuttle is also curved on one side, and such shuttles 36 are positioned in a casing J having an opening N along the top from front to rear and also having an opening in front thereof between the shuttles and the recesses K, L, L, to permit the arm B to pass between the shuttles. The recesses K, L, L, correspond in shape to the projections, G, H, H, and are so constructed that the shuttles 36 are loosely held therein, the projections G, H, H preventing displacement of the shuttle when a 70 weft thread 29 is passing round it and each shuttle 36 carries a thread which is drawn from the non-curved end 43, such threads forming a special warp or selvedge thread.

Near the nose ends of the shuttles 36 are 75 positioned two pivoted spring controlled gates M, M which are primarily intended to divert the threads on to the outside of the shuttles 36 on the return journey of the rod 28, after the arms B of the rods 28 in 80 their forward journey have acted upon same and pushed them open and the springs have returned them to their normal position.

In operation and after the warp threads P are crossed in the usual manner before 85 applying the weft threads, the rod or rods 28 is or are projected across the fabric E, carrying with it or them the weft threads 29 in the form of loops and then the pivoted arms B pass through the opening N and strike the gates M, M open them and pass by them, carrying with them the weft threads 29 the gates M, M closing under action of the springs and on the return journey the arms B will become straightened or nearly 90 straightened out with the rods 28 and the weft threads 29 will be pulled up against the gates M, M which are preferably curved or angled, and the threads will ride over same and pass over the noses F and around 95 the shuttles 36 and under the projections H, H which loosely fit the holes L in the shuttle carrier, such action carrying the loops of the weft threads around their respective special warp or selvedge thread 100 or threads drawn from the shuttle or shuttle 36 whereby the weft threads are retained at the selvedges of the fabric remote from the

weft supply. After the return movement of the rod or rods 28, the usual action of the warp threads takes place. A repeat movement of the rods then occurs.

5 What we do claim as our invention and desire to secure by Letters Patent is:—

1. In looms wherein the wefts are drawn from stationary supplies, mechanism for operating the weft thread comprising a reciprocatory member, a track for guiding said member, and an arm hinged to said member to carry the weft thread, in combination with a selvedge shuttle for the weft thread, a casing for the shuttle having holes therein, 10 the shuttle having a spring-controlled gate at its nose end and having projections extending into said holes in the casing, said reciprocatory member acting on the spring-controlled gate to open and pass the same 15 and carry the weft thread beyond it during the outward journey and draw the 20

weft thread loop around the selvedge shuttle and a selvedge thread drawn therefrom during the return journey of said member.

2. In looms wherein the wefts are drawn 25 from stationary supplies, mechanism for operating the weft thread comprising a reciprocatory member having a weft carrying arm pivoted thereon, in combination with a shuttle, and a gate cooperative therewith, 30 the gate being located in the path of said arm whereby it will be deflected thereby when said member is advanced, and the gate being movable, after said arm has passed it, into a position to deflect the weft 35 thread around the shuttle during return movement of said member.

In testimony whereof we have hereunto set our hands.

ARTHUR WILLIAM GREEN.
JAMES ROBERT GREEN.
PERCY FRENCH.
